UNITED STATES PATENT OFFICE.

GEORGE H. KIDNEY, OF PAINESVILLE, OHIO.

MOP.

SPECIFICATION forming part of Letters Patent No. 248,044, dated October 11, 1881.

Application filed May 12, 1881. (No model.)

To all whom it may concern:

Be it known that I, GEORGE H. KIDNEY, of Painesville, in the county of Lake and State of Ohio, have invented certain new and useful Improvements in Mops, which improvements are fully set forth in the following specification and accompanying drawings, in which—

Figure 1 is an elevation of a mop having my improvements, showing the mop in position for mopping. Fig. 2 is a similar view, showing the mop in the act of wringing.

A is a wire frame attached to a cross-head, B, which is secured to a hollow staff, C.

D is a staff or handle fitted to play inside 15 of the hollow staff C, and has a cross-head and wire frame, E. To the said wire frame A and frame E are attached the ends of a mop-cloth, F. Thus far I do not claim these parts as new.

My improvements consist in the combination, with the frame A, of a supplemental bow, G, for the purpose of holding the cloth F onto the end of the frame to prevent its slipping around on the sides of the frame when loose, and to furnish a bearing down onto the cloth 25 to press it onto the floor in the operation of mopping, as seen in Fig. 1.

My improvements further consist in providing a groove, d, in the side of the staff or handle D, and providing the same with a feathered clutch, H, the purpose of which is to hold the handle from turning backward while wringing. The said clutch H consists of a loose ring or sleeve having ratchet-teeth on the lower side to engage with a pin, i, in the end 35 of the hollow staff C. The said clutch has a feather or pin, h, which runs in the groove d of handle D, which prevents the said clutch from turning thereon, but allows it to slide up and down.

40 The operation of this clutch is as follows:

The said groove d does not extend the full length of the staff D, but terminates at a point designated by d². In the operation of wringing the mop the handle is held at an angle of about forty-five degrees with the cloth over 45 the pail. This allows the clutch to slide down to the extent of the groove. The handle D, being drawn up to its full extent within the hollow staff C, draws the mop-cloth up in the frame. Then by turning the handle D the cloth 50 is twisted, and as it is twisted it draws downward on the handle C as the cloth contracts its length, which soon brings the clutch H in contact with the pin i. It then begins to hold the handle C from turning back. This allows 55 the mop to be twisted as tight as may be desired without its untwisting and loosening the strain on the cloth before it is thoroughly wrung out. By this means a very powerful and complete wringing of the entire mop-cloth 60 is obtained. To release the mop-cloth from the twist it is simply done by pulling the handle D upward a little within the staff C to disengage the clutch from the pin i. The strain on the cloth quickly untwists it. The handle D 65 is then pushed down within the staff, and the mop is ready for further work.

Having described my invention, I claim—

The combination of the feathered clutch H with handle D, having the groove d, and the hollow staff C, having pin i, and provided with wire frame A, having loop G, and the cross-heads B and E for holding mop-cloth F, all constructed and operating substantially as shown and described.

G. H. KIDNEY.
